INVENTOR

WILLIAM E. MELAUGHLIN.

BY *Toulmin & Toulmin*.

ATTORNEY'S

UNITED STATES PATENT OFFICE.

WILLIAM E. McLAUGHLIN, OF MIDDLETOWN, OHIO, ASSIGNOR TO THE BARKELEW ELECTRIC MANUFACTURING COMPANY, OF MIDDLETOWN, OHIO, A CORPORATION OF OHIO.

ELECTRIC SWITCH.

Original application filed January 18, 1926, Serial No. 82,028. Divided and this application filed July 12, 1926. Serial No. 121,810.

My invention relates to electric switches and a system of illumination, and is a division of my application Serial No. 82,028, filed January 18, 1926.

5 It is the object of my invention to provide a system of lighting particularly for automotive vehicles controlled by a foot switch, so arranged that upon the depression of the foot switch the lighting system will be converted from bright to dim, or vice versa, and will remain in such a condition until the switch is depressed a second time, when it will be converted back to its original condition.

10 15 It is my object to provide such a switch in combination either with a resistance system using single filaments in the lamps or a non-resistance system using dual filaments in the lamps, or two bulbs.

20 It is a further object to provide such a system and mechanism in combination with the hand-operated switch found on the dash board of a vehicle, or adjacent thereto.

25 It is my further object to provide a switch which, when depressed, will, by its movement, position the contact parts for bringing into play the desired combination in the system to either a resistance or non-resistance circuit, or a bright or dim filament circuit.

30 35 It is my further object to provide, in such a combination, means for positioning positively the switch elements at each operation to insure their accuracy in functioning upon the next operation.

In the accompanying drawings:

Figure 1 is a side elevation of the foot switch with the cover removed placed beneath the floor board shown in section;

40 45 Figure 2 is a similar view showing the switch in depressed position just after the contact members have been rotated;

Figure 3 is a view similar to Figure 1 from the other side of the switch showing the other contact fingers;

Figure 4 is a similar view to Figure 3 save that the switch is in its depressed position;

Figure 5 is a section on the line 5—5 of Figure 1;

50 Figure 6 is a bottom plan view of the switch;

Figure 7 is a section on the line 7—7 of Figure 6;

Figure 8 is a section on the line 8—8 of Figure 7;

55 Figure 9 is a wiring diagram showing the installation of the switch and the system when single filaments are utilized with a resistance in the line, preferably in the hand switch; and

60 Figure 10 is a diagram showing the system employing dual filaments in the lamps, one pair of filaments being used for bright lights and the other pair being used for so-called dim lights.

65 Referring to the drawings in detail, 1 is the floor board of a vehicle which suspends the switch through the medium of the screws 2 which pass through the floor board and through the cover 3 and cup-shaped support 4 of the switch. An inverted U-shaped cover, the bottom of which rests on the cover 3 and shown in section at 5, has the side walls 6 depending over the open side walls of the cup 4 (one of these side walls is broken away 70 in each of the views to show the interior mechanism) in order to enclose the switch.

75 Mounted on the bottom of the cup 4 is a plate of insulating material 7. This plate of insulating material has a plurality of grooves in its upper face, designated 8, in which are placed the bottom plates 9 of their

upstanding contact fingers 10, 11 and 12, which are mounted at substantially right angles to their bottom plates. The three terminal bolts 13, 14 and 15 retain these fingers in position in the grooves in the insulating base 7. The center of the insulating base is provided with an enlarged aperture 16

80 which is adapted to contain a sleeve 17 which projects upwardly through it and above it, said sleeve terminating in a plurality of large teeth 18. The bottom of the sleeve is provided with an annular plate 19, through which the set screw 20 passes. This

85 set screw passes through the bottom of the cup 4, which is designated 21, and also through the insulating plate 7. This ring 19 is also held in position by one of the terminal bolts which holds one of the contact

90 fingers in position. Thus, the sleeve 17 with its teeth 18 is prevented from rotating. The bottom 21 is provided with an aperture 22 to permit the switch plunger 2 to pass back

95 and forth therethrough. This plunger has 100 its downward movement resisted by a heli-

55

cal spring 24 surrounding it, one end of which rests on the bottom 21 and the other end of which engages a shoulder 25 carried on the plunger 23. This plunger also carries a sleeve 26 which has depending teeth 27.

This sleeve is adapted to rotate around the plunger 23 but is also adapted to move with the plunger by reason of its engagement with the shoulder 25 through its shoulder 28.

- 10 These shoulders are held together by the spring 24. Connected to this sleeve 26 are a pair of insulating plates 29 and 30, between which are held semi-circular separated contact segmental rings 31 and 32. These rings 15 are held in position by the pins 33 which pass through them and the insulating plates 29 and 30. Thus, the segmental rings are both reciprocated and rotated with the sleeve 26 and fingers 27. The upper end of the 20 sleeve 26 is also provided with serrated teeth 34 which engage with positioning teeth 35 which depend from a sleeve 36 attached by the plate 37 to the under side of the cover 3.

Referring to the diagrams and particularly to Figure 9, it will be noted that 38 is a ground connected by a wire 39 to a source of current, such as a battery 40 which is connected by the line 41 to the switch terminal 42. This switch terminal is connected 25 to a swinging switch arm 43 and adapted to engage with the terminal 44 or the terminal 45. Between these terminals is a resistance 46. The terminal 44 is connected by the wire 47 to the contact finger 12. The 30 terminal 45 is connected by the wire 48 to the contact finger 13. This terminal in turn is connected by one of the contact segmental rings 31 or 32, which is connected at its other side to the contact finger 10. The contact finger 10 is connected by the wire 49 to the wire 50 which leads to the filaments 51 and 52, the other sides of which are grounded with the grounds 53 and 54.

Referring to Figure 10, it will be noted that the ground 38 is connected by the wire 39 to the battery 40. From the battery 40 by the wire 41 it is connected to the terminal 42 which is connected to the switch member 43 and to terminal 44. The terminal 44 is connected by the wire 55 to the contact finger 10 which in turn is connected by the contact rings 31 or 32 to either of the contact fingers 12 or 13. If it is connected to the contact fingers 12 then the circuit is made through the wire 56, wire 57 to the two filaments 58 and 59 which are likewise grounded at 60 and 61. If the engagement of 31 is with the contact finger 13 then the circuit will include the wire 62, the wire 63, the filaments 64 and 65 which are grounded at 66 and 67.

Method of operation.

In the case of the resistance circuit using 65 single filaments, if the operator places the

hand switch for the lights to be bright, then the depression of the foot switch will rotate the contacts so that when they return they will be in dimming position and the lights will be dim and will remain dim until another depression and revolution of the contacts, when they will be restored to bright position.

In the case of dual filaments, when the circuit is made for the lamps, for the bright 75 filaments are on, then the depression of the plunger will convert the circuit over to the dim filaments. This circuit will remain until the plunger of the foot switch is depressed once more whereupon the lights will 80 be restored to bright, by bringing the bright filaments in circuit.

Thus the entire control of the character of the lights may be secured without disturbing the hand switch by the operation of 85 the foot button, thus eliminating any danger of the operator taking his attention from the road and his hands from the steering wheel to operate any mechanism on the dash board.

It will be understood that I desire to comprehend within my invention such modifications as may be necessary to adapt it to varying conditions and uses.

Having thus fully described my invention, what I claim as new and desire to secure by Letters Patent, is:

1. In a switch, a reciprocating plunger, a reciprocating and rotating contact member carried thereby, means to rotate said rotating contact member, contact fingers adapted 100 to engage with said rotating reciprocating contact member, said contact fingers being so arranged that a portion thereof will always be engaged with said contact member and others will be alternately engaged, and 105 means to position said rotating contact member to hold it in predetermined position until another actuation and rotation thereof.

2. In a switch, a support, a reciprocating plunger passing therethrough and actuated 110 thereby, yielding means to resist the movement of said plunger, a sleeve carried therewith and adapted to turn thereon, contact members carried on said sleeve insulated therefrom, means on said sleeve adapted to 115 engage with rotating means at the end of the stroke of the plunger, rotating means, and a plurality of contact fingers adapted to engage said contact members, one of said contact members always being in engagement with one of said contact fingers.

3. In a switch, a support, a reciprocating plunger passing therethrough and actuated thereby, yielding means to resist the movement of said plunger, a sleeve carried therewith and adapted to turn thereon, contact members carried on said sleeve insulated therefrom, means on said sleeve adapted to engage with rotating means at the end of the stroke of the plunger; rotating means, 125

and a plurality of contact fingers adapted to engage said contact members, one of said contact members always being in engagement with one of said contact fingers, means carried on said sleeve for positioning it on the return stroke, and positioning means for cooperating therewith.

4. In a switch, a support, a plunger carried thereby reciprocating therethrough, yielding means resisting the movement of said plunger, a sleeve carried thereby adapted to rotate thereon, insulating supporting members mounted on said sleeve having fragmentary contact members, fragmentary contact members; contact fingers adapted to engage therewith, depending teeth from said sleeve having cam faces, a second sleeve spaced therefrom adjacent said plunger having cooperating cam faces adapted when engaging with the first mentioned cam faces to rotate said sleeve.

5. In a switch, a support, a plunger carried thereby reciprocating therethrough, yielding means resisting the movement of said plunger, a sleeve carried thereby adapted to rotate thereon, insulating supporting members mounted on said sleeve having fragmentary contact members, fragmentary contact members, contact fingers adapted to engage therewith, depending teeth from said sleeve having cam faces, a second sleeve spaced therefrom adjacent said plunger having cooperating cam faces adapted when engaging with the first mentioned cam faces to rotate said sleeve, a set of positioning fingers on the upper end of said sleeve and a second set of stationary positioning fingers adapted to cooperate therewith to position said sleeve and maintain it in position.

6. In combination in a switch of a supporting casing, an insulating base therefor, a plurality of spaced contact fingers disposed thereon, a reciprocating plunger passing through said casing therebetween, yielding means engaging with said plunger and said casing for resisting the movement of the plunger, a sleeve mounted on said plunger adapted to reciprocate therewith and rotate thereon, insulating supporting means mounted on said sleeve, contact members carried on said insulating supporting members adapted to engage with the contact fingers, cam fingers depending from said sleeve, stationary cam fingers projecting upwardly from the bottom of said casing adapted to engage said first mentioned cam fingers when the sleeve is reciprocated, and means adapted to connect said contact fingers in an electrical circuit.

7. In combination in a switch of a supporting casing, an insulating base therefor, a plurality of spaced contact fingers disposed thereon, a reciprocating plunger passing through said casing therebetween, yield-

ing means engaging with said plunger and said casing for resisting the movement of the plunger, a sleeve mounted on said plunger adapted to reciprocate therewith and rotate thereon, insulating supporting means mounted on said sleeve, contact members carried on said insulating supporting members adapted to engage with the contact fingers, cam fingers depending from said sleeve, stationary cam fingers projecting upwardly from the bottom of said casing adapted to engage said first mentioned cam fingers when the sleeve is reciprocated, and means adapted to connect said contact fingers in an electrical circuit, positioning fingers on the upper end of said sleeve adapted to engage with stationary depending positioning fingers carried by said casing, and depending stationary fingers carried by said casing.

8. In combination, a U-shaped supporting casing, an inverted U-shaped cooperating cover, a top arranged therebetween, means to suspend said casings, a plunger adapted to reciprocate therethrough, yielding means to resist said reciprocation, a plurality of contact fingers arranged thereabout with the plunger operating therebetween, an insulating support within the casing for said fingers, terminal members adapted to position said fingers and connect the fingers to a circuit, a plurality of cam members arranged on a sleeve on the bottom of the casing around the plunger, a plurality of cooperating cam members adapted to travel with the plunger and rotate thereon connected to a sleeve, a sleeve carrying insulating contact members, insulated contact members adapted to alternately engage some of said contact fingers and constantly engage one of them, yielding means to resist the movement of one of them, yielding means to resist the movement of said plunger arranged within said sleeve and cam members.

9. In combination, a U-shaped supporting casing, an inverted U-shaped cooperating cover, a top arranged therebetween, means to suspend said casings, a plunger adapted to reciprocate therethrough, yielding means to resist said reciprocation, a plurality of contact fingers arranged thereabout with the plunger operating therebetween, an insulating support within the casing for said fingers, terminal members adapted to position said fingers and connect the fingers to a circuit, a plurality of cam members arranged on a sleeve on the bottom of the casing around the plunger, a plurality of cooperating cam members adapted to travel with the plunger and rotate thereon connected to a sleeve, a sleeve carrying insulating contact members, insulated contact members adapted to alternately engage some of said contact fingers and constantly engage one of them, yielding means to resist the

- movement of one of them, yielding means to resist the movement of said plunger arranged within said sleeve and cam members, depending positioning fingers around said 5 plunger carried by said casing, and cooperating positioning fingers adapted to engage therewith carried on the upper end of said sleeve.
10. In a switch, a casing, a reciprocating plunger, a spring for returning said plunger to its normal position, a rotatable sleeve having a pair of contact members to engage with said fingers, cam means above and below said contact members and connected to 15 said sleeve, but insulated therefrom, rotat-

ing means at the bottom of said casing to cooperate with the cam means below the contact members, and positioning means at the top of said casing to cooperate with the cam means above said contact members, whereby 20 when said plunger is depressed, said contact members are rotated so that one will engage with a different pair of said contact fingers and when said plunger is permitted to return to its normal position, said sleeve is 25 positioned so that said sleeve will be rotated when said plunger is depressed.

In testimony whereof, I affix my signature.

WILLIAM E. McLAUGHLIN.
